UNITED STATES PATENT OFFICE.

VICENTE A. RACAZA, OF CEBU, PHILIPPINE ISLANDS.

ELECTRIC RETOUCHER.

1,385,887.

Specification of Letters Patent. Patented July 26, 1921.

Application filed May 20, 1920. Serial No. 382,842.

To all whom it may concern:

Be it known that I, VICENTE A. RACAZA, a citizen of the United States, residing at Cebu, Cebu, Philippine Islands, have invented certain new and useful Improvements in Electric Retouchers; and I do hereby declare the following to be a full, clear, and exact description of the invention, such as will enable others skilled in the art to which it appertains to make and use the same.

This invention has relation to certain new and useful improvements in retouchers and has for its primary object, the provision of an electric retoucher which will be of simple construction and operation and highly efficient in use.

The invention has for another object, the provision of an electric retoucher which is specially adapted for use by photographers for retouching photographic plates and films and which will be operated in such a manner that the most delicate operations of retouching may be performed quickly and efficiently without danger of injury to the film.

The invention has for a further object, the provision of an electric retoucher which will be of simple and compact form and constructed in such a manner that the operator or retoucher may conveniently hold the device and operate the switch thereof with the thumb or a finger to start or stop operation of the retoucher, as desired.

The above and other objects, in view, as will appear as the description proceeds, the invention consists in the novel combination and arrangement of coöoperating elements employed to produce the complete device, as will be hereinafter more specifically set forth, claimed and shown in the accompanying drawings forming a part of this application and in which:—

Figure 1 is an elevation of the complete device.

Fig. 2 is a longitudinal section therethrough.

Fig. 3 is a transverse section on the plane of line 3—3 of Fig. 2, looking in the direction indicated by the arrows.

Fig. 4 is a detail view of the lead carrying tube and parts connected therewith removed from the casing.

Fig. 5 is a diagrammatic view of the wiring, showing the circuit in order that the operation may be clearly understood.

Referring more in detail to the drawings,

in which similar reference characters designate corresponding parts throughout the several views, 1 indicates the cylindrical casing which tapers toward its forward end and has an offset portion 2 on one side intermediate its forward and rear ends. The rear end is closed by a screw cap 3 mounted thereon and having an insulated face 4 positioned therein and within which is embedded one end of the leaf spring 5, the opposite end of which is secured upon the rear end portion of the armature 6, by suitable securing members 7. The securing members 7 also serve to secure to the armature 6 and the spring 5, the offset end of the spring contact breaker 8, which latter has the platinum tip or contact point 9 on its outer or free end portion normally contacting with the point of the contact screw 10 which is threaded through the upper side of the casing 1, as clearly shown in the drawings. The armature 6 is preferably of elongated form and is normally spaced from the electromagnet 11, which latter is mounted upon the inner face of the insulating supporting plate 12 which is secured to the casing 1 and closes the lower open side of the offset portion of said casing 1, suitable securing members 13 being employed to secure the supporting plate 12 in position opposite the adjustable contact screw 10. A switch 14, preferably of the push button type, is positioned in one side of the casing 1 and normally held in open position; the purpose of which will presently appear. The current conducting wires 15 leading from the opposite poles of a battery 16 or other suitable source of supply of electric energy, are extended into the casing 1 by way of the opening 17 in the side of the offset portion 2 of the casing 1, one of the wires being connected with the spring 5, as shown in the drawings, while the opposite wire or remaining wire 15 is connected with the electromagnet 11 in the usual manner, as also shown in the drawings. A wire 18 is extended from the electromagnet 11 to one point 19 of the switch 14. Leading from the opposite point 20 of the switch 14 is the current conducting wire 21 which connects with the contact screw 10, thereby completing a circuit through the electromagnet 11 to energize the latter and draw the armature 6 toward the magnet, thereby withdrawing the contact point 9 of the spring 8 from engagement with the contact screw 10,

against the action of the spring 5. The spring 5 will immediately act to return the armature 6 and bring it to normal position, thereby closing the circuit through the electromagnet 11 and deenergizing the same.

As soon as the point 9 of the screw 8 returns to engagement with the spring 10, however, the circuit will again be completed through the electromagnet 11 to energize the latter and cause a second movement of the armature 6 toward the magnet 11. This operation will be continued as long as the switch 14 is closed over the switch contact points 19 and 20, causing a continual oscillation or vibration of the armature 6. The contact screw 10 may be readily adjusted in the side of the casing 1 to regulate the length of the movement or vibration of the armature 6 the advantages of which will presently appear.

The casing 1 is preferably formed of insulating material and has its tapered forward end open, as shown at 22 and through which projects the forward longitudinally slotted end 23 of the pencil or lead carrying tube 24, the inner end of which connects with the forward end of the armature 6. The lead member 25 of the retouching pencil may be readily engaged within the tube 24 with its pointed ends projecting therefrom and in order to securely clamp the lead 25 in position, I have provided a conical collar or tubular clamping member 26 having both ends open and its forward end rounded, as shown at 27. The inner end portion of the clamping member 26 is interiorly threaded, as shown at 28 for adjustable engagement on the exteriorly threaded forward end portion 29 of the tube 24, inwardly of the forward end of the casing 1. It will therefore be seen that when the lead 25 is engaged in the tube 24 and the clamping members 26 engaged over the tapered end of the lead 25 and threaded upon the tube 24, the forward end of said tube 24 with its longitudinal slots therein will clamp around the lead 25, owing to the tapered shape of the clamping member 26, to securely hold the lead 25 in adjusted position, thereby presenting outwardly of the end of the clamping member 26 the proper portion of the tapered or pointed end of the lead 25. It will also be seen that the exterior diameter of the portion of the clamping member 26 extending through the open end 22 of the casing 1 is less than the diameter of the open end 22, thereby permitting free oscillation or vibration of the tube 24 and the lead 25 therein with the armature 6 during use of the device.

From the foregoing description, taken in connection with the accompanying drawings, it will be evident that it will simply be necessary for the operator to grasp the handle, move the device to position opposite the portion of the photographic plate or film to

be retouched and hold the device while pressing inwardly the switch 14 to complete the circuit through the electromagnet 11, thereby causing proper oscillation or vibration of the lead pencil 25 while the points thereof are in contact with the film.

The most delicate operation in the work of retouching may be performed with this device even by those who are not sufficiently skilled to perform this work by hand, as such operations by hand call for considerable knowledge in this art and ability to move the hand freely and accurately at the wrist, and also move the arm at the elbow and shoulder.

The lines can be applied to the film without injury thereto and in such a manner as to remedy defects in the film and also prevent printing of wrinkles and other objectionable lines and marks on the photograph which may either have been photographed from the subject or caused to appear on the film as the result of injury thereto or a slight defect in the film.

This form of electric retoucher may be readily employed in all operations of retouching and will sufficiently perform the work in a much shorter time than can be done by hand.

While the preferred embodiment of the invention has been shown and described, it will be understood that I do not wish to be limited thereto, as many minor changes in the details of construction and arrangement of parts may be resorted to within the scope of what is claimed without departing from the spirit of the invention.

What is claimed is:—

1. An electric retoucher comprising a casing having open ends and offset intermediate portion, an electromagnet mounted in said offset intermediate portion and insulated from the casing, a cap for closing one end of said casing, an armature to be attracted by said magnet, resilient supporting means for the armature carried by said cap, and a lead carrying member carried by said armature.

2. An electric retoucher comprising a casing having an offset open portion, a plate closing said offset open portion and composed of an insulating material, an electromagnet carried by said plate, an armature within said casing to be attracted by said electromagnet when the latter is energized, means for closing one end of said casing, resilient means carried by the last mentioned means for supporting said armature in spaced relation with respect to said electromagnet, electrical connections between said electromagnet and said resilient supporting means, a contact member carried by said resilient supporting means, a second contact member adapted to be normally engaged by the first mentioned contact member, electrical connections between the second mentioned contact member and the electromagnet.

3. An electric retoucher comprising a casing having an offset open portion, a plate closing said offset open portion and composed of an insulating material, an electromagnet carried by said plate, an armature within said casing to be attracted by said electromagnet when the latter is energized, means for closing one end of said casing, resilient means carried by the last mentioned means for supporting said armature in spaced relation with respect to said electromagnet, electrical connections between said electromagnet and said resilient supporting means, a contact member carried by said resilient supporting means, a second contact member adapted to be normally engaged by the first mentioned contact member, electrical connections between the second mentioned contact member and the electromagnet.

net, a switch in the path of the last mentioned electrical connections, and a lead carrying member carried by said armature.

3. An electric retoucher comprising a casing having open ends and offset intermediate portion, an electromagnet mounted in said offset intermediate portion of the casing and insulated therefrom, an armature within said casing, a cap for one end of said casing, 10 means carried by said cap and connected with said armature to resiliently support the latter in spaced relation with said electromagnet, a lead carrying member projecting from said armature and extending through 15 the remaining open end of said casing, means for clamping a lead member within said lead carrying member, means for completing a circuit through said electromagnet to energize the latter and attract said armature, 20 and means to automatically break the circuit through said armature to permit said armature to return to normal position.
4. An electric retoucher comprising a casing, an electromagnet within said casing, an 25 armature within said casing and normally spaced from said electromagnet, a lead carrying member carried by said armature and extending from one end of said casing, a lead member clamped in said lead carrying 30 member, a cap for the opposite end of said casing, a spring support positioned in the

last mentioned end of said casing and connected with said armature to support the latter in normal position, a movable circuit breaking member connected with said spring support, an adjustable circuit breaking member mounted in said casing and contacting with said movable circuit breaking member, a battery, connections between one end of said battery and said resilient support for the armature, connections between the remaining pole of said battery and said electromagnet, a switch mounted in said casing, electrical connections between said electromagnet and one point of said switch, 40 and electrical connections between the remaining point of said switch and said adjustable circuit breaking member, whereby upon closing of said switch a circuit may be alternately completed through said electromagnet to attract said armature and broken to permit said armature to return to normal position, causing an oscillation of said armature and said lead carrying member when the switch is closed. 50

In testimony whereof I affix my signature in presence of two witnesses.
